[57] CLAIM

The ornamental design for a refrigeration unit, as shown
and described.

DESCRIPTION

FIG. 1 is a top plan view of a refrigeration unit showing
our new design;

FIG. 2 is a front elevational view thereof;

FIG. 3 is a bottom plan view thereof;

FIG. 4 is a rear elevational view thereof;

FIG. 5 is a left side elevational view thereof;

FIG. 6 is a right side elevational view thereof; and

FIG. 7 is a front perspective view thereof.

The shading on the filter media in the front of the refrigeration
unit is understood to repeat uniformly across the
circumscribed area.

FIG. 1

FIG. 5

FIG. 2

FIG. 3

FIG. 6

FIG. 4

FIG. 7
